UNITED STATES PATENT OFFICE.

RALPH E. BARKER, OF LYNN, MASSACHUSETTS, ASSIGNOR TO GENERAL ELECTRIC COMPANY, A CORPORATION OF NEW YORK.

ELECTRIC MOTOR.

No. 797,396.

Specification of Letters Patent.

Patented Aug. 15, 1905.

Application filed October 26, 1903. Serial No. 178,508.

To all whom it may concern:

Be it known that I, RALPH E. BARKER, a citizen of the United States, residing at Lynn, in the county of Essex and State of Massachusetts, have invented certain new and useful Improvements in Electric Motors, of which the following is a specification.

This invention relates to the construction of dynamo-electric machines, and more particularly to small electric motors, such as those used to drive fans, in which simplicity and compactness are features of primary importance. In the design of these small motors special attention is given to reducing the size and number of the parts as much as possible for a given output and arranging these parts to occupy a minimum space. In working toward these ends some difficulty has been experienced in properly securing the field-coils in place. It has been found that the coils sag and change their shape after considerable use, and unless some means is adopted for preventing or at least limiting this sagging a portion of the coil not properly secured against movement may sag until it rubs against the armature, causing undue friction and resulting disastrously unless stopped immediately. It is therefore highly necessary that the coils be so secured that movement to a position of danger to the coils themselves or to the other parts of the motor is positively prevented. For this purpose I have provided adjustable coil-supporting devices for the several field-coils having holding members which extend around the coils and are held at one end by the pole-pieces and at the other end by tie-rods on which the holding members can be adjusted. By this construction the coils may be drawn tightly back on the pole-pieces and closely in around them and held securely in position.

The novel features of my invention will be definitely indicated in the appended claims.

The details of construction will be better understood by reference to the accompanying drawings, which show one embodiment of my invention, and in which—

Figure 1 is a top view of a motor equipped with my improvements. Fig. 2 is an elevation of the same broken away and sectioned in part, and Fig. 3 is a perspective view of the coil-supporting device.

In the drawings I have shown my improve-

ments as applied to a ceiling fan-motor, but it must be understood that the improvements are equally applicable to motors and generators of any description.

1 indicates the pole-pieces, which are cast integral with the shell 2, which forms the frame of the motor and which has the form of a cylinder drawn in on opposite sides at the pole-pieces. Secured to the top and bottom of the cylindrical shell 2 by bolts 3 3 are the end shields 4 4, each of which is a curved arm extending across the end of the shell and provided with a central opening forming a bearing for the shaft 5, which carries the armature 6, the commutator, and the fan-blades. The upper end shield 4 is formed with projections 7 7, on which are mounted the brush-holders carrying brushes bearing on the commutator. The field-coils 8 8 fit over the pole-pieces, as shown in the drawings. Each coil is provided with two coil-holders 10 10, each of which extends around the coil at the middle of one side, as shown in the drawings, and is bent over at one end against the back of the pole-piece or into an opening therein. The other ends of the holders 10 10 extend back and are tied together by a tie-rod 9, extending through openings in the ends of the coil-holders and threaded to receive nuts 11 11, by which the holders are positioned on the rod. The coil-holding members 10 10 are formed from flat metallic strips, and the part in contact with the coil conforms to its shape to prevent damaging the coil. It will be seen that by this construction tightening up the nuts 11 11 and thus moving the ends of holders 10 10 toward each other on rod 9 draws the field-coils 8 8 back on the pole-pieces and also close in around them, and that when once adjusted the coils will be held firmly in the desired position. A casing 12 of ornamental design incloses the motor and is secured to the shell 2.

I do not wish to be understood as limited to the precise construction shown, as many modifications can be made therein without departing from the spirit of my invention, and all such modifications I consider within the scope of my invention.

What I claim as new, and desire to secure by Letters Patent of the United States, is—

1. In a dynamo-electric machine, a pole-piece, a coil thereon, and means engaging with

portions of the coil for adjusting it to conform to the shape of the pole-piece and holding it in its adjusted position.

2. In a dynamo-electric machine, a pole-piece, a coil thereon, and means for drawing the coil in around the pole-piece and a portion thereof back on the pole-pieces.

3. In a dynamo-electric machine, pole-pieces, coils thereon, and means for drawing the middle portions of the coils back on the pole-pieces.

4. In a dynamo-electric machine, a pole-piece, a coil thereon, and means for securing the coil on the pole-piece, comprising a coil-holding member engaging the coil and braced on the pole-piece.

5. In a dynamo-electric machine, a pole-piece, a coil thereon, and an adjustable coil-supporting device comprising a support and a coil-holding member engaging the coil and adjustably mounted on the support.

6. In a dynamo-electric machine, a pole-piece, a coil thereon, and a coil-supporting device comprising a support and a coil-holding member mounted at one end on the support, braced at the other end on the pole-piece and engaging the coil between its ends.

7. In a dynamo-electric machine, a pole-piece, a coil thereon, a shaft, a rod parallel

thereto, and coil-holding members engaging the coil, mounted on said rod near its ends and braced on the pole-piece.

8. In a dynamo-electric machine, a pole-piece, a coil thereon, a shaft, a rod parallel to the shaft, coil-holding members engaging the coil, loosely mounted on the rod near its ends and braced on the pole-piece, and means for adjusting said coil-holding members on the rod.

9. In a dynamo-electric machine, a pole-piece, a coil thereon, a shaft, a rod back of the pole-piece and parallel to the shaft, coil-holding members loosely mounted on the ends of the rod, extending partially around the coil and bearing on the back of the pole-piece, and adjusting nuts on the rod.

10. In a dynamo-electric machine, a pole-piece, a coil thereon, a clamp engaging portions of the coil for drawing said portions back on the pole-piece and thereby drawing the entire coil snugly around the pole-piece.

In witness whereof I have hereunto set my hand this 23d day of October, 1903.

RALPH E. BARKER.
